CLOCK, SO-CALLED MYSTERIOUS SMALL CLOCK

Charles Hilaire Henri Rodanet, Neuilly-sur-Seine, France, assignor to Societe Anonyme: Etablissements Ed. Jaeger, Levallois-Perret, France

Application May 25, 1937, Serial No. 144,590
In France June 18, 1936

4 Claims. (Cl. 58—26)

Clocks, so-called mysterious small clocks, are known having a transparent front face and a transparent rear face, the front face forming a dial and the rear face carrying a central pivot system also serving to set the clock right. The Patent No. 2,060,531, for instance, describes such a small clock. In these small clocks, the minute-hand is driven by an intermediate transparent disc, therefore invisible, which receives a continuous movement of rotation from a mechanism usually arranged in the base of the small clock and which engages with this disc at its periphery the minute-hand actuating the hour-hand, by means of a suitable set of wheels arranged in the central pivot system. In case the intermediate transparent disc receives a movement of oscillation, a selecting device (for instance having a pawl and ratchet) is arranged, moreover, in the central pivot system and transforms this movement of oscillation of the transparent intermediate disc into a movement of rotation of the minute-hand of constant direction. In these small clocks, the mysterious character is attenuated by the fact that an opaque hub is provided at the center of the dial.

The present invention is adapted to remedy this objection and for that purpose it is particularly characterised by the fact that between the fixed transparent front and rear faces forming a dial are arranged two intermediate transparent discs carrying the members indicating the minutes and hours, these discs being rendered rigid at their periphery with gear wheels respectively meshing with toothed wheels arranged in the base of the small clock and rotatively driven at suitable speeds from a suitable chronometric mechanism also arranged in this base, the gear wheels rigid with the transparent intermediate discs being concealed by opaque raised portions secured on the opaque peripheral frame of this small clock.

The present invention also includes a number of detail objects forming a part of the main object, applied separately or in any combinations.

1. Each of the transparent intermediate discs is fitted into and rendered rigid with a toothed peripheral gear wheel which is supported by two spaced rollers arranged in the base of the small clock and on which it rests by its own weight.

2. The chronometric mechanism actuating the transparent intermediate discs is constituted by a small synchronous electric motor starting automatically, receiving current from the mains and provided, in the known manner, with a device determining its direction of rotation.

3. The shaft on which the rotor of the synchronous motor is mounted, is extended at its upper part in order to pass through the opaque frame of the clock and to thus appear through the transparent discs and by its end face which is provided with a reference mark so that it is easy to ascertain if the clock is working.

4. In order to allow of setting the clock right, the shaft on which is rigidly secured the toothed wheel driving the disc carrying the member indicating the minutes, is actuated by a toothed wheel, driven from the chronometric mechanism and connected to this shaft simply by friction, said shaft extending outside the case or base and being provided with a milled knob for facilitating its rotation.

The present invention also extends to a number of particular features which will appear in the following description with reference to the accompanying drawings, given by way of example only, in which:

Fig. 1 is an elevation of the clock according to the invention.

Fig. 2 is a plan view, on an enlarged scale, of the actuating mechanism, the dial, the movable discs and the case or base being removed.

Fig. 3 is a section made according to the broken line III—III of Fig. 2.

Fig. 4 is a section made according to one of the broken lines IV—IV of Figs. 2 and 3.

Fig. 5 is a section, on an enlarged scale, made according to line V—V of Fig. 1.

The mysterious small clock, improved according to the invention, is composed of a base comprising a lower part 1 forming a base and an upper prismatic part 1^a supporting the dial and the movable indicating members, the actuating chronometric mechanism being contained within said base.

According to the invention, the clock is composed of a ring or circular frame 2 secured on the upper part 1^a of the base by any suitable means such as screws 3. On the side faces of this ring respectively are arranged circular discs 4 made of transparent material such as glass, which are held in position by any suitable means. Thus, in the form of construction illustrated, these discs are held in position by a number of members 5 having a cross section in the shape of a flared U and which are secured, by means of screws 6, on ring 2. Moreover, the upper part 1^a of the base comprises two side lugs 21 pressing against the bevelled edge of the glass discs 4. It is obvious that these glass discs 4 might be held in position in any other manner and for instance

by rims screwed or forced on suitable portions of the ring 2.

The ring 2 comprises, on each side of its axial plane passing through the centre line of its circumference, circular recesses 7 and 8 in which are freely arranged with some play, gear wheels 9 and 10 respectively. These gear wheels 9 and 10 are respectively provided with peripheral teeth 11 and 12 meshing respectively with toothed wheels 13 and 14, as explained later on.

In these gear wheels 9 and 10 are respectively secured by any suitable means, intermediate discs 15 and 16 made of transparent material such as glass, on which appear, in any suitable manner, distinctive signs respectively constituting the members indicating the minutes and hours. In the form of construction illustrated in Fig. 1, the member 17 indicating the minutes formed on the glass disc 15 is constituted by a comet whilst the member 18 indicating the hours is constituted by Saturn provided with its ring. It is of course obvious that these distinctive signs might be of any nature whatever. Likewise, one or both of the fixed glass discs 4 have at their periphery a number of distinctive signs 19 regularly spaced apart and indicating the intervals of time, either from minute to minute or from five minutes to five minutes, or from hour to hour, as shown in Fig. 1 in which the signs 19 are in the shape of stars. These various signs 17, 18 and 19, can be obtained either by grinding or engraving the glass or by applying on the latter paint or silvering so that in this latter case the signs appear as mirrors, or in any other suitable manner.

The gear wheels 9 and 10 each rest by their lower part and under the action of their own weight on two spaced rollers 20 journalled in bearing portions provided at the upper part of plates 21 and 22 which are secured, by any suitable means, on a central member 28 itself secured, by screws or bolts 29, on the base 1. Said rollers 20 pass through opening 23 formed in the ring 2 opposite said rollers 20.

In order to conceal all the inner opaque parts and to allow to appear only the glass discs 4, 15 and 16 and to thus create the mysterious character of the working of the clock, two raised members 24 and 25 are arranged on either side of the central ring 2 and are held by their periphery between the side faces of said ring 2 and outer glass discs 4. Said raised members 24 and 25 do not respectively bear against the inner movable transparent discs 16 and 15 so that these discs 15 and 16 can freely rotate, but these raised portions prevent an axial displacement of these discs.

The mechanism for driving the movable transparent indicating discs 15 and 16 will now be described. In the form of construction illustrated on the various figures of the drawings, the chronometric mechanism is electric and constituted by a small synchronous motor supplied with current from the mains, starting automatically and provided, in the known manner, with a device determining the direction of operation so that the rotor 30 of this motor always rotates in the same direction. The stator 54 is secured, by any suitable means, in the lower part of the base 1. The rotor 30 is mounted on a vertical shaft 31 which is supported at 58 at its lower part and journalled near its upper part in a bracket 55 provided in the central member 28. At its upper part the shaft 31 passes through a perforation 56 formed in the central ring 2, so that the end of shaft 31 or a sighting-piece 57

mounted on the said end should be visible through the transparent discs 4, 15, and 16, this allowing the user, in case a reference mark 58 is traced on said end or on the sight-piece 57, to easily ascertain, by the continuous rotation of this reference mark, if the clock is working.

On shaft 31 is provided a worm 32 or the like which meshes with a helical wheel 33 fast on a horizontal shaft 34 journalled at its ends on pivots 35 mounted on the central member 28. One of the ends of shaft 34 comprises a worm 36 meshing with a helical wheel 37 fast on a horizontal shaft 38 journalled in the platens 21 and 22. On this shaft 38 is provided or rigidly secured a toothed pinion 39 meshing with a 15 toothed wheel 40. This toothed wheel 40 drives, by simple friction, a shaft 41. For that purpose, the toothed wheel 40 is pressed by a spring 42 against a bearing 43 fast on shaft 41, the spring 42 taking a bearing, on the one hand, on a washer 44 pressed against the wheel 40 and, on the other hand, on a washer 45 secured by a pin at 46 on shaft 41. At the end of shaft 41 adjacent to platen 22 is rigidly secured the toothed wheel 13 meshing with the teeth 11 of gear wheel 9 the transparent disc 15 of which carries the member 17 indicating the minutes. For that purpose, the speed of the synchronous motor and the gearing down ratios between the gearing systems 32—33, 36—37, 39—40 and 13—11, are so chosen that gear wheel 9 and the transparent disc 15 rigid with the same, effect a complete revolution in one hour.

On shaft 41 is provided a toothed pinion 47 meshing with a toothed wheel 48 fast on a shaft 49 journalled in both platens 21 and 22. At the other end of shaft 49 is provided or rigidly secured a pinion 50 meshing with the toothed wheel 14 which meshes in its turn with the teeth 12 of gear wheel 10 the transparent disc 16 of which carries the member 18 indicating the hours. The toothed wheel 14 is fast on a shaft 51 journalled, at its ends, in the platens 21 and 22. The gearing down ratio of the gears 47—48 and 50—14 is so chosen that the gearing down ratio between toothed wheels 13 and 14, is 12.

Consequently, it will easily be seen from the foregoing that the indicating members 17 and 18 respectively carried by the transparent discs 15 and 16 will respectively indicate the minutes and the hours.

The connection by simple friction existing between the toothed wheel 40, driven from the rotor 30 of the synchronous motor, and shaft 41 is established for the purpose of setting the clock right. For that purpose, shaft 41 extends outside the case or base 1 and on its extension is secured, by a pin 52 for instance, a milled knob 53 by means of which the user can cause shaft 41 to rotate, thus actuating the toothed wheel 13 controlling disc 15 for the minutes and also actuating, through the medium of gears 47, 48, 50 and 14, disc 16 for the hours.

The present invention is not limited to the form of construction described above and illustrated but extends to all those utilising the characteristic features above set forth and satisfying the desired object. These forms of construction can differ particularly by the shape, arrangement and nature of the distinctive signs appearing on the transparent discs, by the shape of the clock, and by the chronometric mechanism driving the transparent discs which can be an electric mechanism or be constituted by an ordinary clockwork actuated by a spring for instance.

What I claim as my invention and desire to secure by Letters Patent is:

1. In a clock, in combination: two front and rear transparent plates, one of which constitutes the dial, a support on which said transparent plates are secured, two intermediate transparent discs arranged between said plates, members indicating the minutes and the hours respectively carried by said intermediate transparent discs, two gear wheels respectively secured at the periphery of said intermediate transparent discs and each comprising a smooth cylindrical surface forming a rolling track, two pairs of rollers journalled in said base and on which rest said gear wheels by their smooth surfaces, two toothed wheels also journalled in the walls of said base for respectively meshing with said gear wheels, opaque raised portions pressed against the inner faces of said transparent plates and at their periphery for concealing said gear wheels, a circular ring comprised between said plates and secured to said base, cross members secured on said ring and having bent down edges for laterally pressing said front and rear transparent plates against said ring, a synchronous electric motor starting automatically and having a constant direction of rotation, a vertical shaft rigid with the rotor of said motor and having a reference mark formed on the upper end, said vertical shaft being upwardly extended for passing through a perforation formed in said ring so that through said transparent discs and transparent plates, can be visible the reference mark formed on the upper end of said shaft, in order that the user can easily ascertain if the clock is working, a gearing down device provided with worm wheels and worms interposed between said vertical shaft and that of said toothed wheels driving the transparent disc indicating the minutes, a set of gears interposed between said toothed wheels so that the toothed wheel driving the transparent disc indicating the hours rotates twelve times less rapidly than the other toothed wheel, said motor as well as the worm gearing down device provided with gears being arranged in the base of the clock.
2. In a clock, in combination: two front and rear transparent plates, one of which constitutes the dial, a support on which said transparent plates are secured, two intermediate transparent discs arranged between said plates, members indicating the minutes and the hours respectively carried by said intermediate transparent discs, two gear wheels respectively secured at the periphery of said intermediate transparent discs and each comprising a smooth cylindrical surface forming a rolling track, two pairs of rollers journalled in said base and on which rest said gear wheels by their smooth surfaces, two toothed wheels also journalled in the walls of said base for respectively meshing with said gear wheels, opaque raised portions pressed against the inner faces of said transparent plates and at their periphery for concealing said gear wheels, a circular ring comprised between said plates and secured to said base, cross members secured on said ring and having bent down edges for laterally pressing said front and rear transparent plates against said ring, a synchronous electric motor starting automatically having a constant direction of rotation, a vertical shaft rigid with the rotor of said motor, a gearing down device provided with worm wheels and worms interposed between said vertical shaft and that of said toothed wheels driving the transparent disc indicating the minutes, a set of gears interposed between said toothed wheels so that the toothed wheel driving the transparent disc indicating the hours rotates twelve times less rapidly than the other toothed wheel, said motor as well as the worm gearing down device provided with gears being arranged within said base.
3. In a clock, in combination: two front and rear transparent plates, one of which constitutes the dial, a support on which said transparent plates are secured, two intermediate transparent discs arranged between said plates, members indicating the minutes and the hours respectively carried by said intermediate transparent discs, two gear wheels respectively secured at the per-
- iphery of said intermediate transparent discs and each comprising a smooth cylindrical surface forming a rolling track, two pairs of rollers journalled in said base and on which rest said gear wheels by their smooth surfaces, two toothed wheels also journalled in the walls of said base for respectively meshing with said gear wheels, opaque raised portions pressed against the inner faces of said transparent plates and at their periphery for concealing said gear wheels, a circular ring comprised between said plates and secured to said base, cross members secured on said ring and having bent down edges for laterally pressing said front and rear transparent plates against said ring, a synchronous electric motor starting automatically and having a constant direction of rotation, a vertical shaft rigid with the rotor of said motor and having a reference mark formed on the upper end, said vertical shaft being upwardly extended for passing through a perforation formed in said ring so that through said transparent discs and transparent plates, can be visible the reference mark formed on the upper end of said shaft, in order that the user can easily ascertain if the clock is working, a first horizontal shaft journalled in the side walls of said base, a gearing down device interposed between said vertical shaft and said first horizontal shaft, a first toothed pinion fast on said first horizontal shaft, a second horizontal shaft on which is rigidly secured that of said toothed wheels driving the transparent disc indicating the minutes, a third

toothed wheel frictionally mounted on said second horizontal shaft and meshing with said toothed pinion for normally driving said second shaft but for allowing said second horizontal shaft to be rotated when it is desired to set the clock right, a milled knob fast on the end of said second horizontal shaft and outside the base for facilitating this operation of setting the clock right, a set of

gears interposed between said toothed wheel driving the disc indicating the minutes and the toothed wheel driving the disc indicating the hours, said motor as well as the worm gearing down device provided with gears being arranged 5 within said base.

CHARLES HILAIRE HENRI RODANET.
